US00D752624S

(12) United States Design Patent
Butcher et al.

(10) Patent No.: US D752,624 S
(45) Date of Patent: * Mar. 29, 2016

(54) DISPLAY SCREEN OR PORTION THEREOF
WITH GRAPHICAL USER INTERFACE

(71) Applicant: Apple Inc., Cupertino, CA (US)

(72) Inventors: Gary Butcher, San Jose, CA (US);
Imran Chaudhri, San Francisco, CA (US); Kevin Will Chen, Sunnyvale, CA (US); Alan C. Dye, San Francisco, CA (US); Jonathan P. Ive, San Francisco, CA (US); Pedro Mari, Santa Cruz, CA (US); Brian Andrew Schmitt, San Francisco, CA (US); Christopher Wilson, San Francisco, CA (US)

(73) Assignee: Apple Inc., Cupertino, CA (US)

() Term: 14 Years

(21) Appl. No.: 29/501,092

(22) Filed: Sep. 1, 2014

(51) LOC (10) Cl. 14-04

(52) U.S. Cl.

USPC D14/486

(57) CLAIM

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

The FIGURE is a front view of a display screen or portion thereof with graphical user interface showing our new design. The outermost broken lines in the FIGURE show a display screen or portion thereof, and form no part of the claimed design. The other broken lines in the FIGURE show portions of the graphical user interface that form no part of the claimed design.
